(57) **CLAIM**

The ornamental design for an egg tray as shown and described.

DESCRIPTION

FIG. 1 is a top perspective view of the egg tray according to the invention.

FIG. 2 is a bottom perspective view of the egg tray of FIG. 1.

FIG. 3 is a top view of the egg tray of FIG. 1.

FIG. 4 is a bottom view of the egg tray of FIG. 1.

FIG. 5 is a left side view of the egg tray of FIG. 1; the right side view is a mirror image.

FIG. 6 is a front view of the egg tray of FIG. 1.

FIG. 7 is a rear view of the egg tray of FIG. 1; and, FIG. 8 is a top perspective view of the egg tray of FIG. 1, shown in use with environmental subject matter of exemplary eggs and a sleeve.

The broken lines are shown for the purpose of illustrating both exemplary environmental subject matter as well as the edges of a symbolic break. None of the broken lines form a part of the claimed design. The appearance of any portion of the article between the break lines forms no part of the claimed design.

1 Claim, 7 Drawing Sheets
